United States Patent Office

Des. 185,823
Patented Aug. 4, 1959

185,823

PAPER CUTTER

Wilhelm Auer and Harry B. Kipp, Irondequoit, N.Y.

Application March 26, 1957, Serial No. 45,440

Term of patent 3½ years

(Cl. D74—1)

FIG. 1

FIG. 2

FIG. 3

Fig. 1 is a front elevational view of a paper cutter showing our new design.

Fig. 2 is a side elevational view of same.

Fig. 3 is a top plan view thereof.

The bottom end of the paper cutter is open.

We claim:

The ornamental design for a paper cutter, substantially as shown and described.
